METHOD OF MANUFACTURE OF REVOLVING
WIRE, FIBER, OR BRISTLE BRUSHES

Frederick Parker Rigby, Sheffield, England

Application April 28, 1934, Serial No. 722,951
In Great Britain May 6, 1933

2 Claims. (Cl. 300—21)

The invention comprises an improved method of manufacturing rotary brushes in which the bristles are secured by hooked pins clenched through a binding of fine gauze and over a length of wire, the ends of the wire being secured together. Units of this kind are built up by riveting between end plates into circular brushes.

Referring to the accompanying drawing Figure 1 shows the method of obtaining the lengths 10 of secured bristles. A steel base plate A with a lengthwise slot and transverse cuts B, suitably spaced to hold pointed and hooked pins C. A length of wire gauze of suitable width is laid on the base plate over the cuts therein. The bristles 15 are placed thereon. A length of wire F, is now pressed by the aid of a grooved and serrated knife G, through the lengthwise slot in the base plate taking the whole of the components with it. This action bends the bristles and then 20 clenches the pins C, through the gauze D, and over the length of wire F.

The effect is shown in Fig. 2.

The resulting length of secured bristles is now bent into an annular disc and the ends of the 25 wire in the root of the bristles secured by twisting them together.

Any desired number of these annular discs when punched are secured by means of rivets between thin metal end plates. Alternatively a

longer length of secured bristles can be bent into spiral form and secured between thin metal end plates in a similar manner shown in Fig. 3.

By clamping the resulting annular discs with the thin metal end plates fitted, between end plates of wood or metal an improved revolving brush is obtained.

I claim:—

1. The steps in the method of manufacturing revolving brushes by supporting bendable pins in 10 spaced parallel relationship to each in a common plane, disposing gauze above the pins, placing bristles on the gauze, disposing a core upon said bristles, and forcing the core and thereby the bristles and gauze into a channel shape and simultaneously bending and anchoring the pins in 15 the wire gauze to secure the bristles.

2. The steps in the method of manufacturing revolving brushes by supporting bendable hook ended pins in spaced parallel relationship to each 20 in a common plane, disposing gauze above the pins, placing bristles on the gauze, disposing a core upon said bristles, and forcing the core and thereby the bristles and gauze into a channeled shape and simultaneously bending the pins and 25 anchoring the hooks in the wire gauze to secure the bristles.

FREDERICK PARKER RIGBY.
